RING

Filed Aug. 20, 1928

Inventor

Joseph Joel

By *Clarence A. O'Brien*
Attorney

UNITED STATES PATENT OFFICE

JOSEPH JOEL, OF LOS ANGELES, CALIFORNIA

RING

Application filed August 20, 1928. Serial No. 300,741.

The present invention relates to a finger ring and has for its prime object to provide means for detachably mounting an insert in the ring.

5 Another very important object of the invention resides in the provision of means of this nature which is simple in construction, inexpensive to manufacture and thoroughly efficient and reliable.

10 With the above and numerous other objects in view as will appear as the description proceeds, the invention resides in certain novel features of construction, in the combination and arrangement of parts as will be 15 hereinafter more fully described and claimed.

In the drawing:

Figure 1 is a side elevation of the ring embodying the features of my invention,

20 Figure 2 is a sectional view therethrough showing the insert,

Figure 3 is an edge view of the ring,

Figure 4 is a sectional view taken substantially on the line 4—4 of Figure 2, and

25 Figure 5 is a fragmentary edge view showing the insert removed.

Referring to the drawing in detail it will be seen that the numeral 5 denotes the ring having a recess 6 formed therein with one end partially bridged as at 7. In the remaining portion of the recess there is provided a transverse partition or lug 8 having an opening 9 therein.

An insert 10 is provided to close the recess 6 and is shaped in proper conformity with the 35 contour and size of the ring and has a substantially ogee shaped spring 11 anchored at one end to one end of the inner surface of the insert so as to be extended through the opening 9 into the recess under the bridge 7 to

40 hold the insert in place. On this insert there may be applied initials, insignia, or indicia of any nature as will be appreciated by those skilled in this art, and therefore the inserts could be sold as articles of manufacture and 45 separately from the ring.

When it is desired to position the insert end in place on the ring, the spring 11 has its free end placed in the opening 9, and upon slight pressure of the finger, the spring continues 50 through the opening to contact with the bot-

tom of the recess, within the slot, formed by bridging one end of the recess, while the insert is seated on the side walls of the recess to fit snugly between the edge of the bridge and the upper edge of one of the end walls.

55

It is thought that the construction, utility and advantages of this invention will now be quite apparent to those skilled in this art without a more detailed description thereof.

The present embodiment of the invention 60 has been disclosed in detail merely for the purposes of exemplification since in actual practice it attains the features enumerated as desirable in the statement of the invention and the above description.

65

It will be apparent that changes in the details of construction, and in the combination and arrangement of parts may be resorted to without departing from the spirit or scope of the invention as hereinafter claimed or 70 sacrificing any of its advantages.

Having thus described my invention, what I claim as new is:

A finger ring of the class described comprising an elongated recess formed on the periphery thereof, said recess being provided with a bottom, side and end walls, and having one end thereof bridged over to provide a substantially closed extension having an opening communicating with the recess, an apertured 75 lug mounted in the recess adjacent said opening, an insert for covering the recess, adapted to rest on the side walls of the recess to fit snugly between the edge of said bridge and the upper edge of one of said end walls, a 80 spring anchored at one end of said insert and adapted to pass through the apertured lug and to terminate within said extension for frictional engagement with the bottom wall thereof.

90

In testimony whereof I affix my signature.
JOSEPH JOEL.
